US00D771128S

(12) **United States Design Patent** (10) **Patent No.:** **US D771,128 S**
Butcher et al. (45) **Date of Patent:** **** Nov. 8, 2016**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, San Jose, CA (US);
Imran Chaudhri, San Francisco, CA (US); **Alan C. Dye**, San Francisco, CA (US); **Aurelio Guzmán**, San Jose, CA (US); **Britt Nelson**, San Francisco, CA (US); **Wan Si Wan**, Sunnyvale, CA (US)

(73) Assignee: **Apple Inc.**, Cupertino, CA (US)

(**) Term: **15 Years**

(21) Appl. No.: **29/540,798**

(22) Filed: **Sep. 28, 2015**

Related U.S. Application Data

(63) Continuation of application No. 29/501,109, filed on Sep. 1, 2014.

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface showing our new design.

The broken lines in the Figure show a display screen or portion thereof and form no part of the claimed design.

1 Claim, 1 Drawing Sheet
(1 of 1 Drawing Sheet(s) Filed in Color)
